UNITED STATES PATENT OFFICE.

GEORGE E. TURNER, OF NEW LEXINGTON, OHIO.

DIPPER FOR EXCAVATING MACHINES.

Application filed December 28, 1924. Serial No. 758,063.

To all whom it may concern:

Be it known that I, GEORGE E. TURNER, a citizen of the United States, residing at New Lexington, in the county of Perry and State of Ohio, have invented certain new and useful Improvements in Dippers for Excavating Machines, of which the following is a specification.

This improvement relates to an improved 10 dipper for excavating purposes and preferably relates to the dippers employed by steam shovels, particularly the large size shovels used for stripping coal and similar uses. Heretofore great difficulty has been 15 encountered by reason of the front wall of the dipper breaking or cracking and if the wall was made thick enough and heavy enough to support the plows, the proper heat treatment of the metal of the wall could 20 not be made. In other instances where the wall was not made thick or heavy, the plows were necessarily supported above the front wall and in that event there was great difficulty encountered with the clogging of the 25 dirt at the mouth of the bucket.

This improvement is intended to overcome the foregoing objections and the front wall is formed of such a character, and the fastenings for the plow or point securing 30 same to the front wall are of such character as to avoid the objections set forth above. In a general way, the front wall may be said to be made in two parts—an upper and a lower plate—and these upper and lower 35 plates are braced by longitudinal supporting walls, and the fastening device is so arranged as to dispense with rivets and openings through the front wall.

Referring to the drawings, Fig. 1 is a 40 side elevation of an ordinary dipper of the character used with steam shovel excavating machines. Fig. 2 is a bottom plan view of the dipper. Fig. 3 is a sectional view on the line 3—3 of Fig. 1. Fig. 4 is a sectional view on the line 4—4 of Fig. 3, and Fig. 5 is a sectional view on the line 5—5 of Fig. 3. Fig. 6 is a sectional view on the line 6—6 of Fig. 4 and Fig. 7 is a detail view of the plow or point.

This invention is concerned particularly 50 with the top part of the front of the dipper as it appears in Fig. 1. The dipper is formed of a front and a rear part marked respectively 2 and 3. These two parts 2 and 3 are riveted together near the center of the bucket, and consequently, when the

front is to be removed, it is only necessary to separate the front from the rear.

Throughout this specification the part termed the front is that shown at the bottom of Fig. 1, and the rear is at the opposite side, while the top is the part at the left of that figure, and the bottom at the right of Fig. 1.

The front plate of the front is indicated by 6 and the rear plate is indicated by 5 (see Fig. 3). These two plates are braced or tied together by longitudinal supporting walls 7 (see Figs. 5 and 3). These two walls 5 and 6 are spaced apart below the top of the wall, but at the cutting edge the two walls converge to form a supporting portion on which are cast a plurality of nose shaped projecting parts 8 (Figs. 4, 5 and 6), and there is a nose shaped part for each plow or point. This nose shaped piece is formed with a slot as indicated in Fig. 8, and the central part of that slot is bored to receive the tongue or web of the plow as explained more fully hereafter. The tool is usually called a plow because it is shaped like a plow and Fig. 7 shows the formation of the tongue or web indicated by 9, the plow being indicated by 13, and this web is formed with a central boss 10, with a longitudinal opening 11, and a slot 12.

In assembling the point or plow upon the nose shaped piece of the front wall, the web 9 is slipped within the slot formed in said nose shaped piece and the central bored opening of the slotted portion of the nose encircles the central boss 10 of the plow or point, as clearly shown in Fig. 6, and thereby the plow or point is braced against lateral movement by the contacting walls of the nose shaped piece. Before the plow or point is attached to the nose shaped piece a bolt is placed within the opening 11 and a nut 15 held within the slot 12 is secured to the end of the bolt, so as to hold the bolt 14 securely fastened to the tongue of the plow. The upwardly projecting portion of the bolt 14 will then extend into a space formed in the front above the plates 5 and 6 as indicated clearly in Fig. 5, so that by inserting the web 19 within the slotted portion of the nose shaped piece the bolt will also be projected up within that space formed above the front and rear plates and the upper end of the bolt is thereby arranged to be secured at a point where the front and rear plates converge together. The nuts for

securing the upper end of that bolt, marked 16 and 17 are preferably located in a pocket formed in the part of the front wall projecting above the plates, and in this way 5 the plow or point is securely fastened to the projecting part of the front wall without weakening it, and whenever it is necessary to remove a plow or point, the nuts 16 and 17 are removed and the plow then with- 10 drawn, the bolt 14 being removed from the tongue by unscrewing same from the nut 15.

It is therefore manifest that by my improved arrangement the plow is dropped entirely outside of the inside line of the 15 mouth of the dipper so as to avoid any possibility of the mouth becoming obstructed by any projecting part that would interfere with the free passage of the dirt into and through the dipper, and the front wall being formed by two plates securely braced by the longitudinal walls form an adequate support for the plow, having great rigidity 20 and strength, dispensing with the necessity of employing at that point a heavy plate 25 which is apt to break or crack, when the plow is subjected to the great strains incident to the use of a dipper for coal mining and other purposes.

Having described the invention, I claim 30 as follows:

1. In an excavating dipper, the combination of a plurality of plates spaced apart to form one part of a front wall, braces connecting the plates to reinforce same, where- 35 by a trussed part is formed, an unbroken wall projecting beyond said trussed part, having a plurality of pockets formed in its projecting end, plow teeth formed with tongues capable of being enclosed by said 40 pockets and means for securing said tongues within said pockets.

2. In an excavating dipper, the combina-

tion of a plurality of plates spaced apart to form a front wall for said dipper, braces connecting said plates forming a trussed member, an unbroken supporting wall projecting beyond the trussed member having pockets therein formed in vertical alignment with said braces, plow points and means for fastening same to said supporting wall 45 whereby the rear side of the point will lie below the inside of the dipper and the front side of the point will lie substantially in line with the front side of said trussed member. 50

3. In an excavating dipper, the combination of a front wall formed of a plurality of plates spaced apart but braced together, said plates converging together at the cutting end with a nose shaped casting extending therefrom, plows located at the upper end 60 of said front, web shaped walls secured to said plows, bolts extending longitudinally through said nose shaped castings and held within the said web shaped walls. 65

4. In an excavating dipper, the combination of a front wall for said dipper formed of two plates spaced apart but converging together at the upper end, supporting walls connecting said plates, plows secured to the upper end of said front wall extending entirely outside of the opening for the dipper, longitudinal walls between the base and the top of the plow having a longitudinal opening and a slot formed in said walls, a bolt 70 extending longitudinally through the opening in said wall, means for securing the lower end of said bolt to the front wall and means located in said slot for securing the bolt to said longitudinal wall. 75

In testimony whereof, I have hereunto set 80 my hand this 20th day of December, A. D. 1924.

GEORGE E. TURNER.
